UNITED STATES PATENT OFFICE.

VERNE S. BURTON, OF BRIDGEBURG, ONTARIO, CANADA, AND STAFFORD A. BURTON,
OF DETROIT, MICHIGAN.

AUTOMATIC BRAKE CONTROL FOR TRAINS.

1,388,141.

Specification of Letters Patent. Patented Aug. 16, 1921.

Application filed March 27, 1919. Serial No. 285,511.

To all whom it may concern:

Be it known that we, VERNE S. BURTON, a British subject, residing at Bridgeburg, county of Welland, Ontario, Canada, and STAFFORD A. BURTON, a British subject, residing at Detroit, county of Wayne, State of Michigan, have invented a certain new and useful Improvement in Automatic Brake Controls for Trains, and declare the following to be a full, clear, and exact description of the same, such as will enable others skilled in the art to which it pertains to make and use the same, reference being had to the accompanying drawings, which form a part of this specification.

Our invention relates to an automatic brake control for trains, shown in the accompanying drawings and more particularly described in the following specification and claim.

One object of this invention is to provide simple and inexpensive means, in combination with the usual automatic block signal, whereby upon the signal being set at danger, the brakes will be automatically operated to stop the train, should the engineer fail to see the signal—or through failure to pull a switch,—provided in the cab that he may proceed into the "block" ahead when necessary, with caution. Thus if the engineer were asleep or dead—or if he failed to see the signal, the train would be stopped independent of anyone upon the engine thereby preventing a wreck which might otherwise occur.

The control may also be employed to stop a train for an order board if the engine men should fail to see it set at danger.

With the foregoing and other objects in view, which will appear as the description proceeds, the invention resides in the combination and arrangement of parts and in the details of construction hereinafter described and claimed, it being understood that changes may be made in the precise embodiment herein disclosed, without departing from the spirit of the same.

In the accompanying drawings:

Figure 1 is a perspective view showing a section of track, an automatic block signal mast, and a fragment of the auxiliary rails connected with an electric switch operated by the movement of the rod controlling the signal arm.

Fig. 2 is a vertical cross-sectional view

through the case housing the mast signal mechanism, showing the installation of the switch,—the closing of which serves to bring into the circuit the auxiliary rails shown in Fig. 1.

Fig. 3 is a plan view—partly diagrammatic—of a section of the track, showing the auxiliary rails, the signal mast, and the electric connections between the auxiliary rails and main conduit lines.

Fig. 4 is a side elevation of a locomotive with the cab in section;—indicating diagrammatically the brake valve, the cut-out valve in the train-line for running double headers; the magnetically controlled air train-line valve and the electrical connection with the auxiliary rails.

Fig. 5 is a cross-sectional detail through one of the track rails; the auxiliary rails,—showing the relative height of the latter—and the electrical contact members which bear thereon.

Fig. 6 is a diagrammatic detail view of the magnetically controlled air valve connected with the train line.

Fig. 7 is a detail of a spring actuated electric switch, whereby the engineer may open the circuit that he may proceed with caution into an occupied block when necessary.

Fig. 8 is a diagrammatic view of the electrical connection between the auxiliary rails; the main conduit line, and the switch in the signal box,—also the electrical connections between the auxiliary rails and the magnetically controlled air relief valve and switch for opening said circuit shown in Fig. 7.

Referring now to the letters of reference placed upon the drawings:

A, A, denotes the rails of railroad block system having the usual electric connection (not shown) with the semaphore signal B—C, C, indicates a pair of auxiliary rails, tapering at each end, located between the track rails—adjacent to the right hand rail of the track but relatively higher, and at least an engine length from the semaphore where the signal would go "into danger."

D, is a case inclosing the signal mechanism, comprising the usual motor d; a train of gears d', driven by the motor, and the rocker arm d² for shifting the rod E, with which the signal arm E', is connected.

F, is one member of an electric switch,—mounted upon the rod E, but insulated

therefrom,—which co-acts with the member F', (secured to the wall of the case D, but insulated therefrom) in opening and closing an electric circuit between the main conduit line G, G, and the auxiliary rails C, C. F', indicates a spring adapted to act upon the member F, to insure a good electrical contact with the member F', (see Fig. 2).

In the engine cab (see Fig. 4) is an air relief valve P, and H, is a pipe connection with the usual train line of the air brake mechanism (not shown).

I, is the engineer's brake valve, and J, is the usual cut-out cock under the brake valve employed when "double heading." K, denotes a casting bolted to the engine frame and insulated therefrom in which are supported spring actuated contact shoes L, L, adapted to bear upon the auxiliary rails C, C. K', is a projecting stop lug formed on the casting K, to limit the movement of the contact shoes L, L, in one direction.

P', is a rocking arm adapted to actuate the air relief valve P, controlled by a pair 25 of magnets M, M, in circuit with the contact shoes L, L, bearing upon the rails C, C. N, is a spring actuated switch in said circuit (see Figs. 7 and 8) which is held normally closed but whereby the engineer may 30 open the circuit in order that he may proceed with caution into an occupied "block," as will be hereafter explained.

Having now indicated the several parts by reference letters, the construction and 35 operation of our invention will be readily understood.

For the purpose of this description, it will be assumed that the semaphore signal has been set to indicate "danger ahead,"—therefore the auxiliary rails C, C, are electrically charged from the line wires G, G, due to closing the switch, comprising the member F, (actuated by the vertical movement of the rod E, controlling the signal 40 arm) and the coating stationary member F', secured to the wall of the case D, on the semaphore mast.

The engine having reached that portion 45 of the track adjacent to the auxiliary rails C, C,—the contacting shoes L, L, will ride up the tapering ends of the rails and close the circuit between the rails and the magnets M, M, thereby charging the latter and causing the rocking arm P', to tilt,—opening 50 the relief valve P, that the air may escape 55 from the train-line to set the brakes, as when under the direct control of the engineer.

The engineer having noted the signal indicating "danger ahead", he may if necessary, proceed with caution into the "block" ahead by holding open the spring actuated switch N,—thereby breaking the circuit between the rails C, C, and the magnetically controlled relief valve P,—until the locomotive has passed the end of said rails. The magnets M, M, having been demagnetized, due to the shoes L, L, being carried beyond the rails C, C, the lever controlling the relief valve is manually returned to its normal position by the engineer,—thereby closing the valve.

The auxiliary rails C, C, are relatively higher than the track rails in order that the contact shoes L, L, need not project 75 downwardly to a point where they might be injured through contact with "turn outs" or other railroad crossings. They are tapered at their ends in order that the contact shoes L, L, may easily ride upon them. 80

Having thus described our invention, what we claim is:—

A railway electric block signal including a post, a swinging semaphore arm, a casing mounted on the post, a vertically movable rod in the casing which can be connected with the semaphore arm, a motor located within the casing at the bottom thereof, a vertical train of gears connected at the lower end with the motor and extending upwardly 90 therefrom, a rocker arm connected with the train of gears at the upper end thereof and also connected with the vertically movable rod for raising and lowering the same and an electric switch operated by the vertically 95 movable rod and composed of a contact member located within the casing at one side of the rod, an insulating member mounted on the interior of the casing and supporting the said contact member, a yieldable brush carried by the rod and having a free terminal portion movable over the insulating member onto and off of the contact member and a spring carried by the rod and bearing against the brush intermediate of the ends thereof for urging the same toward the insulating member and the contact member.

In testimony whereof, we sign this specification in the presence of two witnesses.

VERNE S. BURTON.
